UNITED STATES PATENT OFFICE.

EDWARD L. FLINN, OF FORESTVILLE, OHIO, ASSIGNOR OF ONE-HALF TO
ARTHUR O. HERZOG, OF MADISONVILLE, OHIO.

TIE-PLATE.

No. 843,595.

Specification of Letters Patent.

Patented Feb. 12, 1907.

Application filed May 5, 1906. Serial No. 315,316.

To all whom it may concern

Be it known that I, EDWARD L. FLINN, a citizen of the United States, residing at Forestville, in the county of Hamilton and State 5 of Ohio, have invented certain new and useful Improvements in Tie-Plates, of which the following is a specification.

The object of my invention is to provide a tie-plate of improved construction; and my 10 invention consists in the combination and arrangement of parts hereinafter described and claimed.

In the drawings, Figure 1 is a section through a rail, showing a tie-plate embodying my invention in use; Fig. 2, a top plan view of Fig. 1; Fig. 3, a sectional side view of Fig. 1; and Fig. 4, a perspective view, on an enlarged scale, of the tie-plate turned upside down.

20 The tie-plate proper is in the form of a flat plate A, having a shoulder B overlapping one edge of the flange c of rail C. On the other side the tie-plate is provided with openings a, located along the edge of the rail-flange and through which spikes D are driven into tie d, with their heads engaging the gede of the rail-flange. Outside of shoulder B the edge of the plate is provided with notches a', through which spikes E are driven, with their 25 heads engaging the plate. The shoulder B is intended to be placed on the outside of the rail, in which case the outside fastening of the tie-plate is made by spikes E, which are driven for their full available length, and thus afford a very secure fastening at the outside of the tie-plate, where there is the greatest strain. On its bottom the plate is provided 30 with blades or ribs F and G, adapted to be pressed into the tie d. The outside blades F are made slightly wider than the inside blades and notches f and g, formed in both sets of blades, the notches preferably extending partly through the blades, thereby leaving a strengthening-rib for the plate through-40 out the length of each blade. In cross-sec-

tion the blades are pointed at their outer ends to form entering edges. Then they are gradually thickened to points f' and g', then they are narrowed to points f'' and g'', and then they are thickened or flared considerably at 50 their juncture with the plate A.

In use it is intended that the tie-plates be placed upon the ties with rails in position and the blades pressed into the ties by passing rolling-stock over them. Then the plates 55 are further secured by the spikes D and E. When the blades are pressed into the ties, portions of wood of the ties are forced and compressed into notches f and g and serve to securely lock the plate against endwise movement. As the blades enter the tie the wood 60 expands into the concavities in the neck of the blade, and thus forms an anchoring-lock against removal of the plate. The notches g in blades G are staggered or placed out of line 65 with notches f in blades F, so that there shall be no cross-section of the plate not reinforced and stiffened by blades F or G.

I claim as my invention

1. The combination of a tie-plate; an overlapping shoulder at one side adapted to engage the rail-flange; holes along the edge of the rail-flange at the other side adapted to receive spikes; notches in the edge of the plate outside the shoulder adapted to receive 70 spikes, and notched blades upon the bottom of the plate adapted to enter the tie, substantially as specified.

2. The combination of tie-plate A; openings a and notches a' in the plate for the reception of spikes; overlapping shoulder B on the plate; blades F and G having thicker outer portions and narrower inner portions, and notches f and g in the blades, and out of alinement with each other, substantially as 80 specified.

EDWARD L. FLINN.
